UNITED STATES PATENT OFFICE.

ARTHUR TERREY, OF HAYES, AND JOHN HOOVER BUTLER, OF EAST KESWICK,
ENGLAND.

ROTARY PRINTING PRESS.

Application filed July 31, 1920. Serial No. 400,454.

(GRANTED UNDER THE PROVISIONS OF THE ACT OF MARCH 3, 1921, 41 STAT. L., 1313.)

To all whom it may concern:

Be it known that we, ARTHUR TERREY and JOHN HOOVER BUTLER, subjects of the King of Great Britain and Ireland, residing respectively, at 26 Keith Road, Hayes, Middlesex, England, and "Hillingdon," East Keswick, in the county of York, England, have invented certain new and useful Improvements Relating to Rotary Printing

10 Presses (for which we have filed an application in Great Britain No. 9399, April 12, 1919, Patent No. 146638), of which the following is a specification.

This invention relates to transmission 15 gear for rotary printing presses and has among its objects to provide effective means for transmitting movement to the plate and impression cylinders of the printing couples, to secure greater economy in the distribution of motive power in a printing 20 press, to reduce the noise and generally to avoid the disadvantages resulting from the use of a series of spur wheels commonly used in printing presses for the transmission 25 of movement to the respective printing couples, distributing drums and other elements of the press.

According to the invention a rotary printing press, having a plurality of sets of printing mechanism, is provided with means for effecting the rotation of the plate and impression cylinders, ink distributing drum and other moving elements of the said sets, comprising a number of transmission shafts 30 each common to a number of sets of printing mechanism, worms carried by each transmission shaft and serving to rotate one or more of the rotary elements of each of the respective sets of printing mechanism 35 driven by that transmission shaft by means of worm wheels or spiral toothed or helical wheels, a motor directly coupled to each transmission shaft, and means to ensure the same angular velocity for all such transmission shafts.

According to the invention also in a modification there may be provided a single motor directly coupled to a transmission shaft, and one or more similar transmission shafts 40 receiving motion by a drive from the motor or the directly driven transmission shaft by means serving also to ensure the same angular velocity for all the transmission shafts.

The application of the invention is hereinafter described with reference to the accompanying diagrammatic drawings.

Figure 1 represents in side elevation a multiple deck printing press provided with horizontally disposed transmission or worm shafts each driven by a separate motor 55 mounted on the press frame.

Figure 2 is a part plan corresponding to Figure 1 to illustrate the position of the worm wheels in relation to the cylinders.

Figure 3 is an enlarged view in elevation 65 of an impression cylinder with its worm wheel and worm to illustrate a method of mounting the worm bracket on the impression cylinder bearing box.

Figure 4 represents two decks of a printing press operated by a single motor through two horizontally disposed transmission or worm shafts connected by a silent chain.

According to one arrangement applied to a multiple deck rotary printing press as 75 illustrated in Figures 1 and 2, we provide the printing mechanism on each deck to be operated by a separate motor *a* and we employ a transmission shaft *b* to extend along each deck and having worms *c* mounted 80 thereon for engagement with worm wheels *d* mounted upon the spindles of the impression cylinder *e*, plate cylinder *f*, ink distributing drum *g* and ink fountain roller *h*. The worms and worm wheels are provided 85 right or left handed according to the direction of rotation which it is desired to give to the several cylinders. The respective motors *a* are mounted in vertical line in brackets *i* suitably provided for the purpose at 90 one end of the machine. The transmission shafts *b* are disposed parallel and their ends opposite to that at which the motors are provided have mounted thereon bevel wheels *j* to engage with corresponding bevel wheels *k* mounted upon a vertical shaft *l*, or any other means provided such as a silent chain 95 to ensure the synchronous movement of the respective transmission shafts. By such means it will be understood that each of the 100 members of the printing couple is directly operated from the transmission shaft as are also the ink distributing drum and the fountain roller.

It will be understood that any convenient method of mounting the worm drive in

relation to the respective cylinders may be adopted. For example the worms *c* may be loosely mounted upon the transmission shaft *b* so as to be capable of sliding longitudinally along the shaft for adjustment of the cylinders, but may be caused to rotate with the shaft by means of a feather engaging a keyway extending the length of the shaft or any other suitable means for the same purpose may be adopted. The worms *c* may be maintained in position in respect to the cylinders by means of brackets *m* (Fig. 3) secured upon the bearing boxes of the cylinders.

15 It will be also understood that the relative disposition of the transmission shafts with respect to the elements of the sets of printing mechanism which they respectively drive may be modified or varied according 20 to the requirements of particular types of sets of printing mechanism and their disposition or grouping in the press.

It will be understood that the respective moving members or elements of each set of 25 printing mechanism in the printing press that are to be directly driven from the transmission shaft may be disposed at one side or at opposite sides of the transmission shaft. For example a horizontal transmission shaft 30 may be disposed beneath the axis of the plate cylinder and the ink drum and above the axis of the impression cylinder of the respective couples.

It will be understood that movement may 35 be imparted to a number of transmission shafts from a single motor without sacrifice in the utility of the invention. Such an arrangement is shown in Figure 7 wherein the two transmission shafts are connected together by a silent chain device having the chain *o* passing around wheels *p* mounted upon the adjacent extremities of the shafts *b*.

We claim:

45 1. In a rotary printing press having a plurality of sets of rotary printing mechanism, each comprising a plate cylinder, an impression cylinder and an ink distributing drum, means for effecting the rotation of 50 the plate and impression cylinders, and ink distributing drum, comprising a number of transmission shafts each common to a num-

ber of sets of printing mechanism, worms carried by the said transmission shafts and serving directly to cause the rotation of the 55 plate cylinder, impression cylinder and ink distributing drum of each of the respective sets of printing mechanism, and worm, spiral or helical toothed wheels for engagement with the said worms and means for 60 operating the said press, substantially as described.

2. In a rotary printing press having a plurality of sets of rotary printing mechanism, each comprising a plate cylinder, an 65 impression cylinder and an ink distributing drum, means for effecting the rotation of the plate and impression cylinders, and ink distributing drum, comprising a number of transmission shafts each common to a 70 number of sets of printing mechanism, worms carried by the said transmission shafts and serving directly to cause the rotation of the plate cylinder, impression cylinder and ink distributing drum of each of 75 respective sets of printing mechanism, worm, spiral or helical toothed wheels for engagement with the said worms, and means to ensure the same angular velocity for the said transmission shafts and means for operating the said press, substantially as described.

3. In a rotary printing press having a plurality of sets of rotary printing mechanism, each comprising a plate cylinder, an 80 impression cylinder and an ink distributing drum, means for effecting the rotation of the plate and impression cylinders, and ink distributing drum, comprising a number of transmission shafts each common to a 85 number of sets of printing mechanism, worms carried by the said transmission shafts and serving directly to cause the rotation of the plate cylinder, impression cylinder and ink distributing drum of each of 90 the respective sets of printing mechanism, worm, spiral or helical toothed wheels for engagement with the said worms, and gear between the said transmission shafts, and a 95 motor for operating the press, substantially as described.

ARTHUR TERREY.
JOHN HOOPER BUTLER.
